UNITED STATES PATENT OFFICE.

LOUIS MERZBACH, OF NEW YORK, N. Y.

DESIGN FOR A HAND-BAG.

No. 39,619.

Specification for Design.

Patented Oct. 13, 1908.

Application filed July 9, 1908. Serial No. 442,796. Term of patent 3½ years.

To all whom it may concern:

Be it known that I, LOUIS MERZBACH, a citizen of the United States, and a resident of New York, in the county and State of New York, have invented a new, original, and ornamental Design for Hand-Bags, of which the following is a specification, reference being had to the accompanying drawings, forming a part hereof.

Figure 1 is a front view of the bag in perspective. Fig. 2 is a rear view of the bag in perspective.

I claim:

The ornamental design for a hand bag as shown.

LOUIS MERZBACH.

In the presence of—

LESTER F. DITTENHOEFER,
GERTRUDE K. BRENNAN.
